W. R. PARSONS

MEANS FOR OPERATING WINDOW SHADES

Filed Oct. 9, 1920

Inventor:

Winslow R Parsons
By Jno. G. Elliott
Atty.

UNITED STATES PATENT OFFICE.

WINSLOW R. PARSONS, OF SAN DIEGO, CALIFORNIA.

MEANS FOR OPERATING WINDOW SHADES.

Application filed October 9, 1920. Serial No. 415,783.

To all whom it may concern:

Be it known that I, WINSLOW R. PARSONS, a citizen of the United States, and a resident of the city of San Diego, in the county 5 of San Diego and State of California, have invented certain new and useful Improvements in Means for Operating Window Shades, of which the following is a full, clear, and exact specification.

10 This invention relates to improvements in means for operating window shades wound upon and suspended from the top of a window by a spring-actuated roller, heretofore provided with a ratchet and pawl adapted 15 for detachably securing the shade in any of its adjusted positions, and which requires that the shade or cord suspended therefrom shall be constantly held and manipulated by hand until the desired adjustment is made 20 and the pawl is locked to the ratchet.

The skill required for adjusting and securing such window shades in their adjusted position is beyond the skill of a child, and with all the skill that a grown-up may 25 have from long practice, it not infrequently occurs that, after the exercise of great patience, in the effort to secure the shade in its adjusted position, it will slip from the hand of the operator and very rapidly wind, 30 for its full length, upon the roller.

Regardless of the means for raising or lowering a window shade, every such shade which, at one end, is free to swing from its point of suspension, is liable to be blown 35 away from the sash by a sudden or prolonged gust of wind to a position beyond the reach of a grown-up person, and so gyrated and twisted and torn as to unfit it, as frequently occurs, for further use. My 40 invention is therefore directed to a remedy for these several objectionable features attending to the window shades, above referred to.

The object of my invention broadly stated, 45 is to provide a means for operating window shades that even quite a young child is able to adjust and secure them in their adjusted position.

A further object of my invention is a 50 means by which it is both possible and practicable to suspend a window shade from a spring-actuated roller by means operating to maintain the shade under a tension constantly maintaining the exposed portion of 55 the shade in a smoothed-out condition and particularly throughout the adjustment for the pintle 9 of the roller, which, as usual,

thereof and continuously in perfect alignment with the spring-actuated roller upon which it is wound.

A further object of my invention is to 60 avoid any necessity for the presence or use of a ratchet and pawl for a shade roller and to have the free end of the shade so connected with the top and bottom bars of the window frame with but a slight change in 65 the bottom bar and devices which are not only very simple, cheap and convenient of operation by a child for adjusting and securing the shade in its adjusted position, and in the absence of any possibility of the shade 70 being blown either outwardly or inwardly beyond said frame, or of its being distorted or injured by wind of less force than is necessary to burst the shade at a point midway between the ends of the exposed portion 75 thereof.

With these ends in view, my invention finds its embodiment in certain features of novelty in the construction, combination and arrangement of parts by which the said objects are attained, all as hereinafter fully described with reference to the accompanying drawings and more particularly pointed out in the claims.

In said drawings,—

Fig. 1 is a perspective view of a window shade in which my invention finds its embodiment in its operative position with the roller therefor and the top and bottom ends of the window frame.

Fig. 2 is a section longitudinally through the top and bottom bars of the frame, with the shade and sustaining devices shown in side elevation.

Fig. 3 is a front elevation of a pulley secured to the top bar of the frame, with its hanger partly in section and more particularly showing the location and arrangement of a friction brake for the pulley.

Fig. 4 is a perspective view of the shade 100 roller, indicating the arrangement of the spring therein for automatically operating the roller and elevating the shade.

Similar characters of reference indicate the same parts in the several figures of the 105 drawings.

The window frame for the sash thereof comprises the usual top bar 5, bottom bar or sill 6, and side bars 7—7, to the side bars of which are secured, in the usual manner, the usual bracket bearing 8 at opposite ends 110 110 for the pintle 9 of the roller, which, as usual,

contains a coiled spring 10 connected at its outer end to the pintle and secured at its opposite end to the roller.

In other words, the roller for the shade 5 may be and preferably is of the well known "Hartshorn" construction, with the ratchet and pawl removed therefrom, and in order that the roller may continuously exert such a force as is necessary to wind the shade 10 for its full length thereon.

Adjacent the underside and centrally of the length of the top bar of the window frame, is a pulley wheel 11 journaled by means of its shaft 12 in a bracket 13 se- 15 cured to the top bar by screws or tacks 14.

Interposed between one and maybe both sides of the bracket and the pulley, is a friction brake 15 for the end of the pulley opposed thereto, which may be of felt, fiber 20 or other suitable material, secured in its operative position by any well known means, and which is adapted to produce sufficient friction to prevent the pulley from running on its bearings, from the force of the pull 25 of the coiled spring for the roller.

Mounted upon and preferably confined in a recess 16 in the bottom bar 6 of the frame, is a smaller pulley 17, of ordinary construction, concealed by a plate 18 provided with 30 perforations for the passage therethrough of the cord 19, passing but once under and around pulley 17 but twice around the pulley 11, as shown in Figs. 2 and 3 the free ends of which are secured to the bottom edge 35 of a window shade 20, provided, as usual, with a stiffening stick 21. As shown in the drawings, a screw eye 22 is passed through the fabric of the shade into the stiffening stick and the ends of the cords are passed 40 through and secured to this screw eye, but any suitable device for connecting the ends of the cord with the bottom edge of the shade may be used, preferably such means as will conceal the ends of the cord or knots 45 therein, if there be any.

The total length of the cord for operating the shade should not be less than the distance between the supporting surfaces 50 of the pulley 11 and that of the bottom bar 55 of the window frame, to provide for lowering the edge of the free end of the shade to contact with substantially the latter surface, and for the purposes of concealing the roller 17 within the bottom bar, the length 55 of the cord is accordingly increased.

My invention, however, essentially finds 60 its embodiment in the suspension of a window shade from a roller provided with a spring operating uninterruptedly to wind the shade upon a roller, and a cord secured at both of its ends to the end of the shade and passing thence over supports respective-

ly secured to the top and bottom cross-bars of a window frame and preferably along the line of the longitudinal center of 65 width of the shade.

Having described my invention, what I claim as new and desire to secure by Letters Patent is:

1. A device for the purpose described 70 comprising in combination a window shade, a suspending roller therefor, a spring operating to wind the shade on said roller, a cord, and means freely supporting said cord from the top and bottom bars of a 75 window frame both ends of which cord are located and secured adjacent to the free end of the shade.

2. A device for the purpose described 80 comprising in combination a window shade, a permanently located suspending roller therefor, a spring operating without inter- 85 ruption to wind the shade on said roller, a cord, and means for supporting said cord from the top and bottom bars of a window frame on a line parallel with the longitudinal center of the shade, the free ends 90 of which cord are secured to and adjacent the free end of said shade.

3. A device for the purpose described 95 comprising in combination a window shade, a suspending roller therefor and immovable 100 bearings for said roller, a spring continu- 105 ously operating to wind the shade on said roller, and pulleys for supporting said cord from the top and bottom bars of a window frame on a vertical line parallel with the longitudinal center of the shade.

4. A device for the purpose described 110 comprising in combination a window shade, a suspending roller therefor, a spring con- 115 tinuously operating to wind the shade on said roller, a cord, pulleys for supporting said cord in a straight line from the top and bottom bars of a window frame and a yield- 115 ing friction brake opposed to one of said pulleys.

5. A device for the purpose described comprising in combination a widow shade, a suspending roller therefor, a spring continu- 110 ously operating to wind the shade on said roller, pulleys secured to the top and bottom 115 bars of a window frame on a vertical straight line parallel with the longitudinal center of the shade and a friction brake opposed to the top pulley.

In witness whereof, I have hereunto set my hand and affixed my seal, this 15th day of September, A. D. 1920.

WINSLOW R. PARSONS. [L.S.]
